CLAIM

The ornamental design for an aircraft aft fuselage stowage locker, as shown and described.

DESCRIPTION

FIG. 1 is a perspective view of an aircraft aft fuselage stowage locker showing my new design as installed on the aft fuselage of an aircraft, which is shown in broken lines for illustrative purposes only;

FIG. 2 is a bottom plan view thereof;

FIG. 3 is a left side, elevational view of my new design, the right side elevational view being a mirror image thereof; and,

FIG. 4 is a rear elevational view thereof.

Fig. 1.

Fig. 2.
